Primary Examiner — Darlington Ly(74) *Attorney, Agent, or Firm* — SCHWEGMAN
LUNDBERG & WOESSNER, P.A.(57) **CLAIM**

The ornamental design for an upper frame of a utility vehicle as shown and described.

DESCRIPTION

FIG. 1 is a right, front perspective view of an upper frame of a utility vehicle of the present application;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions of the upper frame shown in broken lines form no part of the claimed design.

1 Claim, 5 Drawing Sheets(56)
